UNITED STATES PATENT OFFICE.

EDWARD I. WILLIAMSON, OF WEYMOUTH, MASSACHUSETTS, ASSIGNOR OF ONE-HALF TO FRANCIS B. HAWKES, OF WEYMOUTH, MASSACHUSETTS.

EDGE-SETTER.

SPECIFICATION forming part of Letters Patent No. 734,789, dated July 28, 1903.

Application filed May 5, 1903. Serial No. 155,767. (No model.)

To all whom it may concern:

Be it known that I, EDWARD I. WILLIAMSON, a citizen of the United States, residing in Weymouth, in the county of Norfolk and State of Massachusetts, have invented a new and useful Improvement in Edge-Setters, of which the following is a specification.

This invention relates to a new and improved construction, the principal object of which is to provide for the application and employment of heat generated by electricity, and thus do away with the ordinary methods of heating the edge-setting tools.

The nature of the invention is fully described below and illustrated in the accompanying drawings, in which—

Figure 1 is a front elevation of my improved edge-setter. Fig. 2 is a side elevation of the same. Fig. 3 is a rear elevation of the tool-holding plate and the cup-shaped case rigid therewith containing an electrical coil. Fig. 4 is a central vertical section of the same.

Similar letters of reference indicate corresponding parts.

25 a represents a standard supporting a frame b, which provides bearings for the driving-shaft c, on which there is mounted an ordinary pulley d. The outer end of the shaft is provided with a cam e, and surrounding this 30 cam is the eccentric ring f, integral with the rod g, pivotally connected at g', Fig. 1, with the radial bar h, which is rigid with the cup-shaped case k. This case is hollow on its rear side to provide a chamber for an electrical coil l, which is suitably embedded in enamel or similar material, connected with the source of electricity by suitable wires l'. This case is mounted on a stud m and is provided with an integral hub k', which extends 35 to the frame b. On the same stud m is mounted the tool-holding plate n, which is provided with a spring o, one end of which is fast at p to the plate, while the other end is provided with a locking-pin r, which, in 40 connection with a spiral spring s, held on the stud m against the plate n by a nut t, holds the plate n and case k locked together. (See dotted lines in Fig. 2.) The plate n is provided with the ordinary tool-holding studs 45 v, each of which is adapted to support a pair of tools w, not new in this invention.

In this device all provision for heating other than that for accommodating the electrical coil l is done away with. When motion is imparted to the pulley d, the shaft c, by 55 means of the cam e, cam-rod g, and arm h, imparts reciprocating rotative movement to the case k and by means of the locking mechanism to the tool-holding plate n, and thus causes the tool-holders and tools to be vibrated as 60 the tools set against the edges of soles in the manner well known in the art. During this operation the tools are heated efficiently by means of the coil l, (the case k, plate n, and other intermediate parts being of metal 65 and the adjacent portions of the plate and case being held in close contact,) and thus the objections raised by insurance companies and others against edge-setters heated by naphtha or other oils or even gas are obviated. I prefer 70 to apply two tool-holding studs to the plate, as it is convenient to have one being heated while another is in use.

Of course the opposite end of the shaft and frame may be provided with a similar mechanism to that described above.

Having thus fully described my invention, what I claim, and desire to secure by Letters Patent, is—

1. The herein-described improved edge-setter, comprising the frame; the driving-shaft; the metallic case k containing an electrical coil for heating purposes; the metallic tool-holding plate n; a stud upon which said plate and case are mounted; means for holding the 80 said case and plate in contact; suitable tool-holding studs extending from said plate; and mechanism intermediate of the case and driving-shaft whereby reciprocating rotative movement is applied to said case, substantially as and for the purpose set forth.

2. The herein-described improved edge-setter, comprising the frame; the driving-shaft; the metallic case k containing an electrical coil for heating purposes; the radial bar h extending from said case; the cam-rod g eccentrically connected at one end with the driving-shaft and pivotally connected at the other end with the radial bar; the metallic tool-holding plate n; a stud on which said plate and case are mounted; a spring supported by the stud and holding the adjacent faces of

said plate and case in contact; a bolt locking the plate and case together whereby the rotative movement of one is imparted to the other; and suitable tool-holding studs supported by said plates, substantially as and for the purpose described.

In testimony whereof I have signed my

name to this specification in the presence of two subscribing witnesses.

EDWARD I. WILLIAMSON.

Witnesses:

HENRY W. WILLIAMS,
A. N. B. EMERY.
